UNITED STATES PATENT OFFICE

WILLIAM ARTER, OF WORCESTER, AND WARREN F. FRASER, OF WESTBORO, MASSACHUSETTS; SAID FRASER ASSIGNOR TO ARTER GRINDING MACHINE COMPANY, OF WORCESTER, MASSACHUSETTS, A CORPORATION OF MASSACHUSETTS

GRINDING MACHINE

Application filed February 14, 1925. Serial No. 9,107.

This invention relates to machines for shaping metal articles through the use of abrading or grinding elements, such machines being herein referred to as grinding machines.

It is the chief object of the present invention to devise a grinding machine which will handle a great variety of metal parts on a production basis. The invention is especially concerned with a machine of this type adapted to operate on round work, either straight or tapered, and with or without shoulders.

A further object of the invention is to devise a machine of the character indicated which will be so completely automatic as to substantially eliminate the necessity of skill on the part of the machine attendant or workman, to reduce to a minimum the attention required by the machine, and to facilitate the handling of the work, more especially its delivery to the machine and its removal therefrom.

The invention involves a machine of novel organization, and also improvements in the various mechanisms of which the machine is composed, such improvements residing especially in a novel mechanism for controlling the relative approaching movement of the grinding wheel and the device which holds the work in contact with the wheel, automatic mechanism for stopping the operation of the machine when the work has been reduced to a predetermined size, a novel wheel dressing mechanism, and novel means for handling the work and presenting it to or removing it from the machine. These and other features of the invention to be hereinafter described in detail will be readily understood from the following description, and the novel features will be more particularly pointed out in the appended claims.

In the accompanying drawings, Figure 1 is a front elevation of a machine embodying this invention;

Fig. 2 is a side elevation of the machine shown in Fig. 1 with certain of the parts broken away;

Fig. 3 is a vertical cross sectional view on the line 3—3, Fig. 1;

Fig. 4 is a side elevation showing the wheel dressing mechanism;

Fig. 5 is a cross sectional view on the line 5—5, Fig. 4;

Fig. 6 is a cross sectional view on the line 6—6, Fig. 4;

Fig. 7 is a cross sectional view on the line 7—7, Fig. 8, showing part of the mechanism for controlling the rate of approach of the presser head toward the grinding wheel, and apparatus associated with said mechanism;

Fig. 8 is a side view, partly in cross section, of the mechanism shown in Fig. 7;

Fig. 9 is a side elevation, partly in cross section, of the work holder and the mechanism for moving it into and out of cooperative relationship to the grinding wheel;

Fig. 10 is a plan view, partly in cross section, of the mechanism shown in Fig. 9;

Figs. 11 and 12 are vertical, cross sectional views through one side of the grinding wheel and the adjacent parts showing different types of work being operated upon;

Fig. 13 is a side view, partly in cross section, of another mechanism for lifting the work holders;

Fig. 14 is a fragmentary cross sectional view through one of the pockets of the work holder; and

Fig. 15 is an edge view of a small portion 80 of the work holder.

Briefly stated, the machine shown comprises a horizontal grinding wheel with mechanism for supporting and rotating it, a presser head which presses the work against the grinding wheel, and a work holder which is mounted between the presser head and the grinding wheel and positions the work with reference to the wheel. A power driven mechanism is provided for raising and lowering the head, this mechanism being arranged to permit the head to approach the grinding wheel by gravity, and an automatic mechanism is provided to control the rate of this approaching movement. This movement is definitely limited by a stop, and the machine is equipped with mechanisms for automatically stopping the rotation of the grinding wheel and also interrupting the approaching movement when the 100

presser head has arrived in a predetermined relationship to the grinding wheel. The machine also includes a crane for engaging the work holder and moving it into and out of its operative position, a wheel dressing mechanism, and a pump and tank for holding and circulating the lubricant used in grinding. The various mechanisms will be taken up for detailed description in substantially the order in which they have just been mentioned.

Referring first to Figs. 1 and 3, the grinding wheel is indicated at 2, this wheel being mounted on an annular flange 3 which is removably secured to a bracket or wheel support 4 mounted on the upper end of a vertical shaft 5. The bearing mechanism which supports the upper end of this shaft preferably is like that shown in the Arter Patent No. 1,289,358, dated December 31, 1918. Supporting the lower end of this shaft is a tapered sleeve 6, split on one side, which receives an oppositely tapered sleeve 7 that is secured to a stationary part of the machine. A cap 8 is bolted to the lower end of this frame part and has threaded engagement with the sleeve 6 so that this sleeve may be vertically adjusted to take up wear by adjusting the cap 8. It will be observed that the upper bearing 9 for the shaft 5 is of conical form and that it supports the weight of the shaft 5 and the parts carried thereby, the lower bearing 6 being simply a guide bearing. The bearing 9 is supported in a heavy bracket 10 which rests in a central aperture formed in the base 12 of the machine frame.

For the purpose of driving the shaft 5 and the grinding wheel 2, a spiral gear 16 is keyed to said shaft and meshes with another spiral gear fast on a horizontal shaft 17. A pulley 18, Fig. 1, rotates freely on this shaft and has a clutch face arranged to be engaged by a slidable clutch element 19 which is keyed to the shaft and is backed up by a spring 20, this clutch being controlled by a clutch lever 21. The pulley 18 is driven by a belt connection from the pulley 22 on the main driving shaft 24, this shaft carrying a pulley 25 by means of which it may be connected to any convenient source of power.

The work is held against the grinding wheel 2 by an annular presser head 27 which is adjustably secured to the lower end of a vertical shaft or rod 28. This rod is guided in upper and lower bearings 29 and 30, respectively, mounted in the machine frame, these bearings being of the general type of that shown at 6-7 and above described. A universal joint connects the lower end of the rod 28 with the head 27, this joint comprising a spherical member 31 secured rigidly to the rod and upper and lower socket plates 32 and 33, respectively, which are clamped upon the spherical member 31 by means of three bolts 34, Fig. 1. The lower plate 33 is

bolted to the head 27. By loosening the bolts 34 slightly and lowering the head 27 into contact with the wheel 2, and then tightening the bolts 34 again, the head can be secured in absolute parallelism with the upper surface of the wheel 2.

The work holder is normally supported between the driving wheel 2 and the presser head 27. This holder comprises a disk 36, Figs. 3, 9 and 10, which preferably is somewhat concaved, and has a series of pockets 37 to receive the rolls or other pieces of work W. Preferably these pockets are inclined with reference to a radius of the disk, as best shown in Fig. 10, and in order to minimize the tendency of the work to wear grooves in the grinding wheel, the holder is mounted to rotate with the work but about an axis which is eccentric to the axis of rotation of the wheel 2. For this purpose a short pin or stub shaft 38 is secured at the lower end of the slide or rod 28 in an eccentric relationship to the shaft 5, as will be seen from an inspection of Fig. 3, and the work holder has a hub portion apertured to receive this shaft. The shaft or pin 38 is secured in a plate 40 which is bolted to the lower side of the socket plate 33. The work holder, therefore, is rotated by the drag of the work, and as it rotates it moves the pieces of work backward and forward across the face of the grinding wheel and thus distributes the wear.

For the purpose of raising and lowering the presser head 27 a power driven mechanism is provided which comprises a vertical screw threaded shaft 42 mounted immediately behind the rod or slide 28. Threaded on this screw is a nut or follower 43, Fig. 3, having an extension that projects through a vertical slot 41 in the frame of the machine so that the follower 43 can move up or down but cannot rotate. Resting on this nut or follower is a bracket 44 which is rigidly secured to the slides 28. A bevel gear 45 is secured to the upper end of the shaft 42 and is arranged to mesh with two bevel gears 46 and 47, both mounted loosely on the horizontal shaft 48, Figs. 1 and 3. These two gears are provided with clutch portions arranged to mesh with a slidable clutch member 50 which is splined to the shaft 48 and is arranged to be moved backward and forward on the shaft by a shipper 51, Fig. 3. This shipper is secured on the upper end of a vertical rock shaft 52, and a hand lever 53 is secured to this shaft to permit manual operation thereof. Consequently, by moving this lever in one direction or the other, as desired, the shaft 42 may be rotated to raise or lower the presser head 27. Power is transmitted to this mechanism by a belt (not shown) which connects the pulley 54 on the shaft 48 to another pulley 55 on the main shaft 24.

In order to prevent the presser head from overrunning in either its upward or down-

ward movement, the rock shaft 52 has two cam members 56 and 57 adjustably secured thereto, and the bracket 44 carries a pin 58 and the nut or follower 43 carries a pin 59 to engage these cam members. When the shaft 42 is rotating in the proper direction to lift the head 27, the pin 58 will, at a point predetermined by the setting of the cam 56, engage said cam and rock the shaft 52 far enough to throw the shiftable clutch member 50 into its central or neutral position. This stops the upward movement of the presser head. When the mechanism is operating to lower the presser head and the head has reached a point near the lower limit of its movement, the pin 59 will engage the lower cam member 57 and rock the shaft 52 in the opposite direction far enough to throw the member 50 into its neutral position and thus stop the rotation of the shaft 42. This lifting and lowering mechanism for the presser head must, therefore, be thrown into operation manually and it can be stopped by hand, but if it is not so stopped it will stop automatically when the head has reached a predetermined elevation.

As above stated, when the machine is in operation the head 27 holds the work against the face of the grinding wheel 2. It will be evident from an inspection of Fig. 3 that when the mechanism above described is lowering the head, it is not positively producing a lowering movement but is simply allowing the head to drop by gravity at a rate determined by the pitch and rate of rotation of the screw 42. This mechanism cannot produce a positive lowering movement of the head due to the fact that the bracket 44 simply rests on the nut or follower 43, the screw 42 having no positive engagement with the bracket 44. This mechanism, however, is utilized to lower the head into engagement with the work or until stopped, as hereinafter described, and thereafter the follower 43 moves downwardly out of engagement with the bracket 44. If this mechanism alone were depended upon to control the movement of the presser head, it is evident that the work would be subjected to a pressure equal to the entire weight of the head and the parts movable therewith. For some classes of work this pressure is desirable, but for other work it would be too great. Consequently, these parts are made of sufficient mass to produce the maximum pressure desired, and an additional mechanism is provided to control the rate of descent of the head 27, this mechanism being arranged to permit only a very gradual approaching movement of the head toward the grinding wheel so that, in effect, the pressure of the head upon the work can be regulated as desired.

For this purpose the bracket 44 which is rigidly connected with the head 27 is provided with a micrometer screw 60 having a graduated dial 61 arranged to cooperate with a stationary pointer 62. When the head is lowered by the power mechanism above described, it descends with the follower 43 until the screw 60 strikes the stop 63. Thereafter the head can only descend with the stop. The mechanism for permitting the lowering movement of the stop is best shown in Figs. 7 and 8. From an inspection of these figures it will be seen that the stop 63 rests on a wedge 64 which, in turn, is supported by another wedge 65. The inclination of the contacting surfaces of these two wedge members is very slight. A spring 66 bears against one end of the wedge 65, while a screw threaded shaft 67 bears against the opposite end of the wedge. This shaft rotates in an internally threaded stationary bushing 68. Splined to this shaft is the driven member 70 of a clutch, the driving member 71 of which is secured to the face of a worm wheel 72 driven by a worm 73 on a shaft 74 which, in turn, is driven by a worm gear connection with another shaft 75 having a stepped pulley 76 fast thereon. This pulley is driven by round belt connections with another stepped pulley 77, Fig. 1, which is adapted to be driven from a third stepped pulley 78 on the main shaft 24. The driving ratio between the main shaft 24 and the screw shaft 67 thus is very high so that the speed of the shaft 24 is tremendously reduced, a maximum reduction of about three thousand to one being obtained in practice, and this ratio can, of course, be adjusted by the stepped pulley construction above described. As the shaft 67 rotates it is moved very gradually endwise through the bushing 68, thus forcing the lower wedge 64 toward the left, Fig. 7, and allowing the stop 63 to settle very slowly. Since the head 27 cannot descend more rapidly than the stop 63, this mechanism definitely limits the rate at which the presser head can approach the grinding wheel. The rate at which the grinding operation proceeds, therefore, can be controlled by properly adjusting the rate of descent of the presser head. This rate will be adjusted, of course, in accordance with the nature of the work, the character of the grinding wheel used, and other conditions which will be evident to those skilled in this art.

In order to automatically stop this approaching movement when the head 27 has arrived at a predetermined distance from the upper surface of the grinding wheel 2, a wheel 82 having a graduated periphery is secured to the screw shaft 67. A stop 83 projects laterally from this wheel and when the shaft 67 has rotated through a predetermined angle, the pin 83 engages a pin 84 projecting from one arm of a bell crank lever 85 and moves this lever. This movement is transmitted through a lever 86, Fig. 8, rock shaft 87, and clutch shifter 88, Fig. 7, to the clutch member 70, thus disengaging this

130

member from the driving clutch member 71. Thus the rotation of the screw shaft 67 is immediately stopped, and consequently the descending movement of the head 27 is stopped.

5 The movement of the lever 85 produced in the manner just described is also utilized to stop the rotation of the grinding wheel 2. For this purpose the shaft on which the 10 lever 85 is fulcrumed is rigidly connected to the movable valve member 90, Fig. 8. This valve is mounted inside a hollow valve casing 91 to which compressed air is supplied from a pump (not shown). It will be evident 15 from an inspection of Fig. 8 that when the lever 85 is moved in the direction described, the valve 90 will then permit the flow of air through the passages 92 to the cylinder formed in the cylinder block 93. In this 20 cylinder is a piston 94 which is forced toward the left, Fig. 8, by the air admitted as just described. The movement of the piston is transmitted through a bar 95 which is pivoted to the piston and through a yoke 96, Figs. 1, 25 7 and 8, to a rod 97 which is connected to the upper end of the clutch lever 21, above referred to. This movement throws out the clutch against the action of the spring 20, thus disconnecting the grinding wheel from 30 its source of power and causing the wheel to stop.

In order to adjust the extent of the gradual lowering movement of the presser head produced in the manner above described, a 35 tubular sleeve or barrel 100, Figs. 7 and 8, is adjustably secured by a set screw 101 on a reduced portion of the housing 102 that encloses the clutch 70-71 and the driving 40 mechanism associated therewith. This barrel has a stop 103, Fig. 8, to engage a pin 104 on the disk 82. A torsion spring 105 is housed within the barrel 100 and has its outer end rigidly secured to said barrel while its inner end enters a slot in the screw shaft 70. This 45 spring therefore tends to hold the pin 104 against the stationary stop 103. By adjusting the barrel 100 relatively to the stationary casing 102 and securing it in its adjusted 50 position, the angular distance that the pin 83 will have to travel before it strikes the pin 84 can be adjusted.

The spring 105 also performs the function of resetting the screw shaft 67 and the disk 55 82 in their initial positions after the approaching movement has been stopped. That is, the rotation of the shaft 101 produced in the manner above described winds up or tensions the torsion spring 105. After this 60 approaching movement has been interrupted by the disengagement of the clutch member 70 from the member 71, the torsion spring immediately rotates the shaft 67 backwardly until the pin 104 strikes the stop 103. In other words, it returns both the disk 82 and 65 the shaft 67 to their initial positions. As

soon as the workman has moved the lever 53 to effect the raising of the presser head 27, and thus carry the micrometer screw 60 upwardly away from the stop 63, the coiled spring 66, Fig. 7, will then move the wedge 70 65 toward the right, forcing it against the end of the screw shaft 67 and thus resetting the wedge in its initial position.

It will therefore be observed that when the presser head has arrived in a predetermined relationship to the grinding wheel, the gradual approaching movement of the head is automatically stopped, the rotation of the grinding wheel is interrupted, and the parts through which the gradual approaching movement is controlled are automatically reset in their initial positions.

When it is subsequently desired to start this mechanism into operation again, it is simply necessary to throw the lever 85, Fig. 8, into the position shown in said figure, this motion re-engaging the clutch member 70 with its cooperating member 71 and moving the valve 90 into position to permit the escape of air from the cylinder and thus allow the spring 20, Fig. 1, to re-engage the clutch 19 with the pulley 18.

As above stated, the work holder 36 is designed to hold a series of pieces of work in the proper positions on the surface of the grinding wheel 2 as the grinding operation progresses. Preferably this work holder is so constructed that it will also support the articles of work independently of the grinding wheel. That is, the pockets in the work holder, while open at their lower ends, are not wide enough to allow the articles of work to drop through them (see Figs. 14 and 15) the work being placed in the pockets from above or else inserted in the outer ends of the pockets. For convenience in manufacture we prefer to make the holder as shown in Figs. 9 and 10 with a rim 107 which is bolted to the main body 36 of the work holder, the rim itself having the pockets 37 formed therein. The outer margin of this rim is provided with a series of holes 108, Fig. 10 to receive one or more dowel pins that project downwardly from a retaining ring 109 that simply rests on the rim. The ring 109 thus prevents the articles of work from escaping through endwise movement from their pockets in the work holder. It will be understood that the nature of this retaining ring and the manner in which it is supported and to some extent, also, the construction of the work holder 107 will depend upon the nature of the work. For example, Fig. 11 shows a work holder designed for handling poppet valve lifters where the cylindrical portions are to be ground, and in this construction the retaining ring 109' has parts arranged to engage the heads of the valve lifters and limit their outward movement. Also, in Fig. 12, which shows an arrangement adapted for handling

95

100

105

110

115

120

125

130

tapered pins or rolls, the retaining ring 110 is bolted to the outer surface of the presser head 27 but performs essentially the same functions as the ring 109, Fig. 9. For convenience in removing the work holders with the pieces of work loaded in them and replacing them again in operative position in the machine, two cranes preferably are provided mounted on opposite sides of the machine, 5 each crane being a duplicate of the other. Referring to Figs. 9 and 10 it will be seen that each crane comprises an arm 112 pivotally mounted on a shaft 113 which is supported in a bracket 114, Fig. 1. The hub portion of the 10 holder 36 includes a flange 115 and the end of the arm 112 is provided with an open sided recess or slot adapted to receive said hub with the flange 115 resting on the upper surface of the slotted portion of the arm. Secured to the arm 112 immediately above the 15 post or shaft 113 is a cap 116 which is internally threaded to receive a screw 117 having a hand wheel 118 secured thereto. The lower end of this screw bears on a block 119 which rests on the top of the post 113. Consequently, after the arm has been engaged with the holder, as shown in Figs. 9 and 10, this arm and the holder may be lifted together by rotating the hand wheel 118 in the 20 proper direction. When the holder and the work have been raised clear of the grinding wheel 2, it is then a simple matter to swing the arm 112 in the proper direction to carry the holder out of the machine. In the meantime the holder which is supported by the crane at the opposite side of the machine may be swung into its operative position, this holder having previously been loaded with pieces of work while the grinding operation 25 has been going on. The holder just removed may be unloaded and reloaded again in readiness to be moved into operative relationship to the grinding wheel when the machine is again ready to receive it. In order to facilitate the movement of the work holder into alignment with the stub shaft or pin 38, a short arm 120 is secured to or formed integral with the crane arm 112 and is arranged to engage a stop 121, Fig. 10, provided on the 30 base 12 of the machine. As soon as the crane has been operated to position a work holder in the machine, the hand wheel 118 is turned to lower the holder upon the grinding wheel 2, and the arm 112 is then swung out of engagement with the work holder and moved into its idle position.

The wheel dressing mechanism provided by this invention is arranged to be operated either manually or by power, as may be desired. This mechanism is best shown in Figs. 4, 5 and 6. It comprises a bracket 124 pivoted at one side of the grinding wheel 2 and supporting an arm 125 in the end of which a tool holder 126 is mounted. This 35 tool holder may be of the general type now used for this purpose, and it supports a diamond point 127 which constitutes the wheel dressing tool. In performing this wheel dressing operation the tool 127 must move entirely across the working face of the grinding wheel 2, and for this purpose the bracket 124 is clamped securely on a vertical rock shaft 128 which is supported in suitable bearings. Secured to the upper end of this rock shaft is a segment 130 of a worm wheel meshing with a worm 131 secured on a horizontal shaft 132. A hand wheel 133 is splined to the outer end of this shaft so that by rotating this hand wheel the dressing tool 127 may be swung backward and forward across the 40 face of the wheel 2. This tool may be adjusted vertically in the tool holder 126 by manipulating the nut 134 which is threaded on a screw 135 that carries the tool 127.

The power driven mechanism for operating the wheel dresser is arranged to be either connected with, or disconnected from, the shaft 132, as may be desired. For this purpose the hub portion of the hand wheel 133 is provided with a tapered annular clutch member 136 45 adapted to engage with the complementary face of a clutch member 137 which preferably is formed integral with a bushing rotating loosely on the shaft 132 and secured to a worm wheel 138. A nut 139 threaded on the reduced end portion of the shaft 132 bears against the clutch member 136 so that by turning this nut up, the latter clutch member may be moved into driving engagement with the part 137. If the nut 139 is loosened, the 50 part 136 will disengage the clutch member 137. The worm wheel 138 is driven by a worm (not shown) fast on a shaft 140. This shaft has two gears 141 and 142 rotating loosely thereon and each having a clutch face 55 arranged to be engaged with a slideable clutch member 143 which is keyed to the shaft 140. The gear 142 meshes with a gear 144 on another shaft 145, while the gear 141 is driven through an intermediate idler gear from a gear 146 also secured on the shaft 145. This shaft carries a pulley 147 adapted to be belt connected to a pulley 148, Fig. 1, on the main shaft 24. The slideable clutch member 140 60 may be shifted backward or forward by means of a hand lever 150. Consequently, by shifting the lever 150 backward and forward, the operator can cause the mechanism above described to traverse the dressing tool 127 backward and forward across the face 65 of the grinding wheel 2. He can stop this operation at any desired time and readjust the tool 127. This mechanism effects a very slow traversing movement of the tool and it therefore enables an unskilled operator to 70 dress the wheel 2 with an accuracy that otherwise could only be produced by a highly skilled workman. Usually in performing this dressing operation the workman will 75 produce a rough dressing by manually trav-

ersing the dressing tool across the face of the wheel and he will then finish the dressing operation through the use of the power driven mechanism.

5 In using the machine the wheel will first be dressed, as above described. In order to be sure that the lower face of the presser head is absolutely parallel to the surface of the grinding wheel, the operator may lower the 10 presser head down on the grinding wheel while the latter is rotating and keep it there until the wheel has acted on the entire lower face of the presser head. The head is next lifted and the work is then inserted in the 15 machine through the use of the work holder and one of the cranes, as also described above. The operator next moves the lever 53 in the proper direction to cause the head 27 to descend rapidly toward the work, this movement 20 also serving to enter the stub shaft or pin 38 in the aperture of the work holder 36, as shown in Fig. 3. The descent of the head 27 is stopped by the engagement of the head with the work, the follower 43 overrunning 25 and being stopped through the automatic actuation of the clutch shipper 51, as above described. The micrometer screw 60 should now be turned down until it engages firmly with the stop 63, then the head 27 should be raised 30 and the micrometer screw advanced, say, two-ten thousandths of an inch more and the head then allowed to descend until the screw again engages the stop. The operator should previously have adjusted the barrel 100 so that 35 a predetermined reduction in thickness of the work will be produced during the gradual approaching movement of the presser head toward the grinding wheel. This setting can be made accurately due to the fact that the 40 disk 82 is graduated in divisions which correspond to movements of the presser head of one ten-thousandths of an inch. Assuming that the work is to be reduced approximately ten ten-thousandths of an inch, the 45 disk 82 will be correspondingly adjusted and the hand lever 85 will then be moved into the position shown in Fig. 8, thus starting the rotation of the grinding wheel 2 and initiating the operation of the mechanism that limits 50 the rate of descent of the presser head 27. The grinding operation will then commence, the head 27 bearing on the pieces of work and holding them against the upper surface 55 of the grinding wheel, the pressure which it thus exerts on the work, however, being controlled by the rate at which the presser head is allowed to descend. When this head has descended a predetermined distance and the work consequently has been reduced by 60 an amount determined by the setting of the gradual approaching mechanism, the grinding operation will be stopped automatically. The operator may then lift the head 27 through the operation of the power raising 65 and lowering mechanism, remove a piece of

work and caliper it to see if it has been reduced to the required dimensions. If he finds that the work is still a few ten-thousandths over-size he readjusts the disk 82 and starts up the machine again after first lowering 70 the head 27 into contact with the work. Or, he may back off the micrometer screw and dial by the desired amount and then repeat the grinding operation. One or two trials will indicate the proper setting of the disk 82 75 and micrometer screw 60, and thereafter it will be unnecessary to change the setting of these members until a change in work is made, or a change in the setting of the screw is necessary to compensate for wear of the grinding wheel. The setting of the micrometer screw determines the point at which the lowering movement of the head 27 produced by the power raising and lowering mechanism will be stopped and the head brought into the control 80 of the mechanism that effects the gradual approaching movement. It also determines the position of the head 27 at the time of starting the grinding operation. This screw should be so set that when the head is initially brought into contact with the work it will exert approximately the desired pressure 85 on the work for the commencement of the grinding operation.

Another adjustment that may be necessary 90 in starting the machine into operation is to change the relative eccentricity of the work holder and grinding wheel. This is controlled by the adjustment of the bracket 10, Fig. 3, in the base 12 of the machine frame. This bracket is mounted to slide slightly to the left or right, Fig. 3, both the bracket 10 and base 12 being grooved to receive keys 152—152 which permit this sliding movement but prevent the bracket from moving transversely to the direction of said sliding movement. A rod 153 is secured to the bracket 10 and projects through a short upright plate 154 which is bolted to the base 12. This rod is threaded and nuts screwed on to the rod bear against opposite sides of the plate 154. Consequently, by loosening one of these nuts and turning the other, the bracket 10, together with the parts supported thereby, including the grinding wheel 2, may be moved 100 toward the right or left. When adjusted the bracket 10 is secured in position by bolts 155, Fig. 1.

The degree of eccentricity between the grinding wheel and the holder need not be great, but should be sufficient to prevent the work from wearing grooves in the grinding wheel. As the pieces of work roll between the presser head 27 and the grinding wheel 2, they rotate the work holder but at a slower speed than that of the grinding wheel. The eccentricity between the work holder and the grinding wheel results in relatively moving 105 the pieces of work endwise across the face 110 115 120 125 130

of the wheel and thus distributes the wear evenly.

It may also be noted here that since the pieces of work do not set radially on the wheel but at an angle to the radii of the wheel, as is shown in Fig. 10, the action of the grinding wheel is somewhat different from that ordinarily produced. That is, each grain of the grinding wheel which comes in contact with the work, instead of moving directly across the face of the work, has a composite movement with reference to the work which results in producing a finer surface than that made by the more common methods.

The lubricant or other liquid used to flood the work and the parts in contact therewith while the grinding operation is being performed may conveniently be supplied from a tank 156, Figs. 2 and 3. A pump 157 raises the lubricant from this tank and forces it through a pipe 158 into the presser head 27, this head being made hollow and having a series of discharge apertures, as shown in Fig. 3, for the purpose of distributing the lubricant properly to the different points where the grinding operation is taking place. This lubricant drenches the work, flows over the surface of the grinding wheel, and over the upper surfaces of the bracket 10 and base 12. The base is provided with suitable channels to catch the lubricant and conduct it to a spout 160 which returns it to the tank 156. It should be noted that the support 4, Fig. 3, for the grinding wheel is so designed that it prevents the liquid used in grinding from reaching the bearings for the shaft 5.

It will now be appreciated that this invention provides a machine which will handle a great variety of forms of round work on a production basis, while at the same time requiring relatively little skill on the part of the machine attendant. The machine not only is adapted to handle work in relatively large quantities, but it is also capable of producing very accurate work. Furthermore, it is highly automatic, while at the same time being so designed that wear and depreciation are reduced to a minimum.

While we have herein shown and described the best embodiment of our invention that we have so far devised, it will be evident that the invention may be embodied in a great variety of forms without departing from the spirit or scope thereof. For example, it is contemplated that the presser head 27 instead of being made of metal, as above described, may be made of a material having abrasive characteristics. Whether both the presser head and grinding wheel are made of abrasive material, or one only of these members has abrasive characteristics, depends on the requirements of individual machines and the nature of the work which they are required to perform, and is not material from the standpoint of machine organization.

While the grinding wheel and presser head are hereinafter claimed in the relationship in which they have been shown, the use of the head as an abrasive or grinding wheel, as above mentioned, with the work supported on a lower wheel obviously is the equivalent of the specific arrangement shown. Cranes for moving the work holder into and out of the machine, instead of being manually operated may be arranged to be operated by power, if desired. A crane arranged to be lifted by power is shown in Fig. 13. In this arrangement, the arm 112 is constructed and mounted as above described. A cap 162 is bolted to the upper side of the bracket from which the arm extends and is internally bored to form a cylinder in which a stationary piston 163 is mounted. This piston is supported on the top of the post 113, ball bearings being interposed between the piston and the post. Compressed air may be admitted to the cylinder 162 or released therefrom by a manually operated three-way valve 164. It will be evident that when air under pressure is admitted to the cylinder 162 it will lift the arm 112, together with the work holder 36 and the parts supported thereby. This work holder may then be swung into or out of the machine. Subsequently, when it is desired to lower the arm 112 it is simply necessary to move the air valve 164 into the proper position to release the air from the cylinder 162. Various other modifications also may be made.

Having thus described our invention, what we desire to claim as new is:

1. In a grinding machine, the combination of a grinding wheel mounted to rotate in a horizontal plane, a presser head mounted above said wheel and operative to press the work against said wheel, means for rotating said wheel, power driven mechanism for raising and lowering said head to move it toward or from its operating position, additional mechanism for controlling the rate of approach of said head toward said wheel, and a fluid pressure operated means arranged to be brought into action by said additional mechanism to stop the rotation of said wheel.

2. In a grinding machine, the combination of a grinding wheel mounted to rotate in a horizontal plane, a presser head mounted above said wheel for up and down movement and operative to press the work against said wheel, means for guiding said head for vertical movement toward or from said wheel, a part connected with said head to move up and down therewith, a stop arranged to be engaged by said part, a horizontally movable wedge supporting said stop, and power driven mechanism for slowly moving said wedge in a direction permitting said stop to settle gradually and thereby limit the rate of approach of said head toward said wheel.

3. In a grinding machine, the combination of a grinding wheel mounted to rotate in a

- horizontal plane, a presser head mounted above said wheel for up and down movement and operative to press the work against said wheel, means for guiding said head for vertical movement toward or from said wheel, a part connected with said head to move up and down therewith, a stop arranged to be engaged by said part, a horizontally movable wedge supporting said stop, a screw shaft bearing against said wedge, and power operated mechanism for rotating said shaft to move said wedge in a direction to permit said stop to settle gradually and thereby limit the rate of approach of said head toward said wheel.
4. In a grinding machine, the combination of a grinding wheel mounted to rotate in a horizontal plane, a presser head mounted above said wheel for up and down movement and operative to press the work against said wheel, means for guiding said head for vertical movement toward or from said wheel, a part connected with said head to move up and down therewith, a stop arranged to be engaged by said part, a horizontally movable wedge supporting said stop, a screw shaft bearing against said wedge, power operated mechanism for slowly moving said wedge in a direction permitting said stop to settle gradually and thereby limit the rate of approach of said head toward said wheel, and means for automatically interrupting the action of said mechanism when said head has arrived in a predetermined relationship to said wheel.
5. In a grinding machine, the combination of a grinding wheel mounted to rotate in a horizontal plane, a presser head mounted above said wheel for up and down movement and operative to press the work against said wheel, means for guiding said head for vertical movement toward or from said wheel, a part connected with said head to move up and down therewith, a stop arranged to be engaged by said part, a horizontally movable wedge supporting said stop, power driven mechanism for slowly moving said wedge in a direction permitting said stop to settle gradually and thereby limit the rate of approach of said head toward said wheel, means for automatically interrupting the action of said mechanism when said head has arrived in a predetermined relationship to said wheel, and means for automatically resetting said wedge in its initial position after said interruption.
6. In a grinding machine, the combination of a grinding wheel mounted to rotate in a horizontal plane, a presser head mounted above said wheel for up and down movement and operative to press the work against said wheel, means for guiding said head for vertical movement toward or from said wheel, a part connected with said head to move up and down therewith, a stop arranged to be engaged by said part, a horizontally movable wedge supporting said stop, a screw shaft bearing against said wedge, power operated mechanism for rotating said shaft to move said wedge in a direction to permit said stop to settle gradually and thereby limit the rate of approach of said head toward said wheel, said mechanism including a clutch through which power is transmitted to said shaft, and a torsion spring arranged to be tensioned by the rotation of said shaft and operative upon the release of said clutch to automatically return said shaft to its initial position.
7. In a grinding machine, the combination of a grinding wheel mounted to rotate in a horizontal plane, a presser head mounted above said wheel for up and down movement and operative to press the work against said wheel, means for guiding said head for vertical movement toward or from said wheel, a part connected with said head to move up and down therewith, a stop arranged to be engaged by said part, a horizontally movable wedge supporting said stop, a screw shaft bearing against said wedge, power operated mechanism for rotating said shaft to move said wedge in a direction to permit said stop to settle gradually and thereby limit the rate of approach of said head toward said wheel, means for automatically interrupting the action of said mechanism when said head has arrived at a predetermined distance from said wheel, and means for resetting said screw shaft in its initial position after said interruption.
8. In a grinding machine, the combination of a grinding wheel mounted to rotate in a horizontal plane, a presser head mounted above said wheel for up and down movement and operative to press the work against said wheel, means for guiding said head for vertical movement toward or from said wheel, a part connected with said head to move up and down therewith, a stop arranged to be engaged by said part, a horizontally movable wedge supporting said stop, a screw shaft bearing against said wedge, power operated mechanism for rotating said shaft to move said wedge in a direction to permit said stop to settle gradually and thereby limit the rate of approach of said head toward said wheel, means for automatically interrupting the action of said mechanism when said head has arrived at a predetermined distance from said wheel, means for automatically returning said screw shaft to its initial position after said interruption, and a spring for resetting said wedge in its original position after said interruption.
9. In a grinding machine, the combination of a grinding wheel mounted to rotate in a horizontal plane, a presser head mounted above said wheel for up and down movement and operative to press the work against said wheel, means for guiding said head for vertical movement toward or from said wheel, a part connected with said head to move up and down therewith, a stop arranged to be engaged by said part, a horizontally movable wedge supporting said stop, a screw shaft bearing against said wedge, power operated mechanism for rotating said shaft to move said wedge in a direction to permit said stop to settle gradually and thereby limit the rate of approach of said head toward said wheel, said mechanism including a clutch through which power is transmitted to said shaft, and a torsion spring arranged to be tensioned by the rotation of said shaft and operative upon the release of said clutch to automatically return said shaft to its initial position.

- part connected with said head to move up and down therewith, a stop arranged to be engaged by said part, a horizontally movable wedge supporting said stop, a screw shaft bearing against said wedge, power operated mechanism for rotating said shaft to move said wedge in a direction to permit said stop to settle gradually and thereby limit the rate of approach of said head toward said wheel, 5 said mechanism including a clutch through which power is transmitted to said shaft, and means operated by the rotation of said shaft through a predetermined angle for operating said clutch. 10
- 15 10. In a grinding machine, the combination of a grinding wheel mounted to rotate in a horizontal plane, a presser head mounted above said wheel for up and down movement and operative to press the work against said wheel, means for guiding said head for vertical movement toward or from said wheel, a part connected with said head to move up and down therewith, a stop arranged to be engaged by said part, a horizontally movable wedge supporting said stop, a screw shaft bearing against said wedge, power operated mechanism for rotating said shaft to move said wedge in a direction to permit said stop to settle gradually and thereby limit the rate 20 of approach of said head toward said wheel, said mechanism including a clutch through which power is transmitted to said shaft, means for rotating said wheel, and means arranged to be operated by the rotation of said shaft through a predetermined angle to release said clutch and also to stop the rotation of said wheel. 25
- 30 11. In a grinding machine, the combination of a grinding wheel mounted to rotate in a horizontal plane, a presser head mounted above said wheel and operative to press the work against said wheel, power driven mechanism for raising and lowering said head, a micrometer screw connected with said head to move up and down therewith, a stop arranged to be engaged by said screw, a horizontally movable wedge supporting said stop, and power driven means for slowly moving said wedge under said stop in a direction permitting the stop to descend gradually. 40
- 45 12. In a grinding machine, the combination of a grinding wheel mounted to rotate in a horizontal plane, a presser head mounted above said wheel and operative to press the work against said wheel, a vertical slide supporting said head, a shaft mounted parallel to said slide, a manually controlled reversible mechanism for driving said shaft, a nut on said shaft arranged to support said slide, 50 whereby said mechanism is operative to raise or lower said slide and head to move it from or toward operative relationship to said wheel, means operated by said nut for automatically interrupting the rotation of said shaft when the nut has been moved up or 55 down to a predetermined point, and an additional power driven mechanism including a driven member having an inclined surface for limiting the rate of downward movement of said head. 70
13. In a grinding machine, the combination of a grinding wheel mounted to rotate in a horizontal plane, a presser head mounted above said wheel and operative to press the work against said wheel, means for guiding said head for vertical movement toward or from said wheel, mechanism for driving said wheel, a work holder mounted between said wheel and head, and automatic mechanism for stopping the rotation of the grinding wheel 75 when the work has been reduced to a predetermined size. 80
14. In a grinding machine, the combination of a grinding wheel mounted to rotate in a horizontal plane, a presser head mounted above said wheel and operative to press the work against said wheel, means for guiding said head for vertical movement toward or from said wheel, mechanism for driving said wheel, a work holder mounted between said wheel and head, and means for automatically interrupting the grinding action on the work when the work has been reduced to a predetermined size. 85
15. In a grinding machine, the combination of a grinding wheel, a device movable up or down for pressing the work against said wheel, means for rotating said wheel, mechanism for raising and lowering said device to move it toward or from its operative relationship to said wheel, additional mechanism for causing a relative approaching movement of said wheel and said device and for limiting the rate of said approaching movement, said mechanisms being operable independently of each other and at different times, and means for automatically stopping said approaching movement when said wheel and said device have reached a predetermined space relationship. 90
- 10 16. In a grinding machine, the combination of a grinding wheel mounted to rotate in a substantially horizontal plane, a presser head mounted above said wheel for movement up and down relatively to the wheel and operative to press the work against said wheel, power driven mechanism for raising and lowering said head, said head being discon- 105 nectable from said mechanism and arranged to have a lowering movement independently of said mechanism, additional power driven mechanism for limiting the rate of said lowering movement of the head, said additional mechanism including a screw shaft controlling said lowering movement, and said mechanisms being operable independently of each other and at different times. 110
- 115 17. In a grinding machine, the combination of a grinding wheel mounted to rotate in a substantially horizontal plane, a presser head mounted above said wheel for movement up and down relatively to the wheel and operative to press the work against said wheel, power driven mechanism for raising and lowering said head, said head being discon- 120 nectable from said mechanism and arranged to have a lowering movement independently of said mechanism, additional power driven mechanism for limiting the rate of said lowering movement of the head, said additional mechanism including a screw shaft controlling said lowering movement, and said mechanisms being operable independently of each other and at different times. 125
- 130

head mounted above said wheel for movement up and down relatively to the wheel and operative to press the work against said wheel, power driven mechanism for raising and lowering said head, said head being disconnectable from said mechanism and arranged to have a lowering movement independently of said mechanism, additional power driven mechanism for limiting the rate of said lowering movement of the head, said mechanisms being operable independently of each other and at different times, and said additional mechanism including a screw shaft controlling said lowering movement, means for automatically interrupting the action of said additional mechanism when said head has arrived at a predetermined distance from said wheel, and means for resetting said screw shaft in its initial position after said interruption.

18. In a grinding machine, the combination of a grinding wheel mounted to rotate in a substantially horizontal plane, a presser head mounted above said wheel for movement up and down relatively to the wheel and operative to press the work against said wheel, power driven mechanism for raising and lowering said head, said head being disconnectable from said mechanism and arranged to have a lowering movement independently of said mechanism, additional power driven mechanism for limiting the rate of said lowering movement of the head, said mechanisms being operable independently of each other and at different times, said additional mechanism including a screw shaft for limiting the rate of said lowering movement, a clutch through which power is transmitted to said shaft, and a spring arranged to be tensioned by the movement of said shaft and operative upon the release of said clutch to automatically return the shaft to its initial position.

19. In a grinding machine, the combination of a grinding wheel mounted to rotate in a substantially horizontal plane, a presser head mounted above said wheel for movement up and down relatively to the wheel and operative to press the work against said wheel, power driven mechanism for raising and lowering said head to move it toward or from its operative relationship to said wheel, said mechanism including a clutch, automatic means for throwing the clutch into its neutral position to stop the movement of said head by said mechanism, said head being disconnectable from said mechanism whereby it may be freed therefrom and permitted to move downwardly at a different rate from that caused by said mechanism, a positive stop for limiting the downward movement of said head, and additional power driven mechanism for giving said stop a gradual lowering movement.

20. In a grinding machine, the combina-

tion of a grinding wheel mounted to rotate in a substantially horizontal plane, a presser head mounted above said wheel for movement up and down relatively to the wheel and operative to press the work against said wheel, power driven mechanism for raising and lowering said head to move it toward or from its operative relationship to said wheel, said mechanism including a clutch, automatic means for throwing the clutch into its neutral position to stop the movement of said head by said mechanism, said head being disconnectable from said mechanism whereby it may be freed therefrom and permitted to move downwardly at a different rate from that caused by said mechanism, a positive stop for limiting the downward movement of said head, a micrometer screw connected with said head for movement up and down therewith, said screw being arranged to engage said stop, power driven mechanism for giving said stop a gradual lowering movement, and means for automatically interrupting the action of the last mentioned power driven mechanism when the head has reached a predetermined space relationship to said wheel.

21. In a grinding machine, the combination of a grinding member mounted to rotate in a horizontal plane, a presser member for holding the work against said grinding member, one of said members being mounted above the other, means for rotating said grinding member, means for guiding the upper of said members for vertical movement under the influence of gravity toward the other member, and power driven mechanism including a wedge for controlling the rate of said movement.

22. In a grinding machine, the combination of a grinding member mounted to rotate in a horizontal plane, a presser member for holding the work against said grinding member, one of said members being mounted above the other, means for rotating said grinding member, means for guiding the upper of said members for vertical movement under the influence of gravity toward the other member, mechanism for raising and lowering said upper member, and additional means for automatically controlling the rate of said movement, said additional means being adjustable to vary the rate at which said upper member is allowed to approach the lower member.

23. In a grinding machine, the combination of a grinding member mounted to rotate in a horizontal plane, a presser member for holding the work against said grinding member, one of said members being mounted above the other, means for rotating said grinding member, means for guiding the upper of said members for vertical movement toward or from the lower member, power driven mechanism for raising and low-

ering said upper member to move it toward or from its operative position, additional mechanism for automatically controlling the rate of approach of said upper member toward the lower member, said mechanisms being operable independently of each other and at different times, and adjustable means for stopping said approaching movement when the upper member has reached a pre-determined spaced relationship to the lower member.

24. In a grinding machine, the combination of a grinding member mounted to rotate in a horizontal plane, a presser member for holding the work against said grinding member, one of said members being mounted above the other, means for rotating said grinding member, power driven mechanism for raising and lowering said upper member to move it toward or from its operating position, additional mechanism for controlling the rate of approach of said upper member toward said lower member, and means arranged to be brought into operation by said additional mechanism for automatically stopping the rotation of said grinding member.

In testimony whereof we have signed our names to this specification.
